UNITED STATES PATENT OFFICE.

WALTER B. MCFARLANE, OF NIAGARA FALLS, ONTARIO, CANADA, ASSIGNOR OF ONE-FOURTH TO EDWIN POOLE, OF ST. CATHARINES.

HONING AND STROPPING DEVICE FOR SAFETY-RAZOR BLADES.

Application filed March 18, 1925. Serial No. 16,547.

To all whom it may concern:

Be it known that I, WALTER B. MCFARLANE, of the city of Niagara Falls, in the county of Welland, Province of Ontario, Canada, a subject of the King of Great Britain, have invented certain new and useful Improvements in Honing and Stropping Devices for Safety-Razor Blades, of which the following is a specification.

This invention relates to devices intended for holding safety razor blades so that they may be honed or stropped on an ordinary razor strop, and the object of the present invention is to devise such a holder which will be simple and cheap to manufacture, which will have a minimum number of parts, in which the blades may be quickly and easily inserted and removed, which may be held so that the blade may be honed or stropped in exactly the same manner, and which in weight and size will conform very closely to that of the old type straight razor which is still commonly used by barbers.

I attain my object by means of the constructions hereinafter described and illustrated in the accompanying drawings in which

Fig. 1 is a side elevation of my improved device;

Fig. 2 a section on the line 2—2 in Fig. 1; Fig. 3 an end elevation of the device;

Fig. 4 a similar view showing a modification;

Fig. 5 a plan view of the blank from which the device is formed; and

Fig. 6 a front view showing the parts in open position.

In the drawings like numerals of reference indicate corresponding parts in the different figures.

The handle of my improved device is of the conventional razor form consisting of a pair of plates 1 riveted together at one end and having the opposite ends thereof connected by a pivot pin 2.

Connected with this pivot pin 2 is the end of the razor holding device. This razor holding device is bent up from the blank shown in Fig. 5. The blank is bent at 3 and doubled back on itself forming plates 4 and 5 between which the blade to be stropped may be gripped. In the construction shown in Figs. 1, 2 and 3, which is intended for blades of the "Gillette" type, the

plate 4 is provided with projections 6 adapted to pass through the holes in the blade, and the plate 5 is provided with holes 7 into which the projections may extend. The blank will be formed of material with sufficient spring to cause the plates 4 and 5 to normally tend to sufficiently spring apart to enable a blade to be inserted or removed.

In order that the blade may have a proper angle to the face of the strop during the stropping operation, the plate 4 is formed with an extension 8, which is bent, as will be seen in Fig. 3, to form a loop of substantially the width of the back of an ordinary razor.

Integral with the plate 4 is a shank 9, which is pivotally mounted on the pivot pin 2. To stiffen the shank 9, it is preferably bent up to channel form as will best be seen in Fig. 2, and that portion received between the plates 1, is bent up to rectangular form to provide suitable bearing surfaces and will be of such a thickness to provide room between the plates 1 for the blade holder when it is in folded position with the handle.

To hold the plate 5 in blade gripping position, the latter is also provided with a short shank 10, also bent up to channel form, the outside width of the channel being such that it will be received and frictionally engaged within the channel formed by the shank 9. Usually this frictional engagement will be sufficient to hold the plates in razor gripping position, but in any case during the normal stropping operation, the user's thumb will normally rest on the shank 10 while the fingers will extend over the shank 9, so that the plates and shanks will be firmly gripped together.

The shank 10 will, preferably, be provided with a tab 11 for engagement by the fingers to facilitate its disengagement from the shank 9.

For blades of the "Eveready" type, the projections 6 will be omitted, and the stiffening back strip will be received within the loop 8 as indicated in Fig. 4.

As the metal from which the holder is formed must be of a comparatively thick material to give the required stiffness, the plates 4 and 5 will preferably be slightly bevelled to reduce the thickness of the device at the honing edge.

From the above description it will be seen that I have devised a stropping device which

will satisfactorily attain the object of my invention as set out in the preamble of this specification.

What I claim is:

1. In a holder for razor blades during honing and stropping, the combination of a pair of plates connected together at one end in a manner to prevent movement relative to one another in the plane of their adjacent surfaces, and between which a blade may be received, at least one of said plates being formed of resilient material, the free end of said last mentioned plate normally tending to occupy a position spaced from the other plate in a direction normal to their surfaces; and a shank integral with the free end of each plate, one of said shanks having a recess formed therein in which at least a portion on the other shank is adapted to be received when the plates are in blade holding position. 50
2. In a holder for razor blades during honing and stropping, the combination of a pair of plates connected together at one end in a manner to prevent movement relative to one another in the plane of their adjacent surfaces, and between which a blade may be received, at least one of said plates being formed of resilient material, the free end of said last mentioned plate normally tending to occupy a position spaced from the other plate in a direction normal to their surfaces; and a shank integral with the free end of each plate, one of said shanks having a recess formed therein in which at least a portion on the other shank is adapted to be received when the plates are in blade holding position. 60
3. In a holder for razor blades during honing and stropping, the combination of a pair of plates connected together at one end in a manner to prevent movement relative to one another in the plane of their adjacent surfaces, and between which a blade may be received, at least one of said plates being formed of resilient material, the free end of

said last mentioned plate normally tending to occupy a position spaced from the other plate in a direction normal to their surfaces; and a shank integral with the free end of each plate, one of said shanks having a recess formed therein in which at least a portion of the other shank is adapted to be frictionally engaged when the plates are in blade holding position. 75

4. In a holder for razor blades during honing and stropping, a strip of resilient metal doubled upon itself to form a pair of plates connected together at one end in a manner to prevent movement relative to one another in the plane of their adjacent surfaces, and between which a blade may be received, the free end of one plate normally tending to occupy a position spaced from the free end of the other plate in a direction normal to their surfaces; and a shank integral with the free end of each plate, one of said shanks being bent into channel shape in cross section to receive and frictionally grip the other shank. 85

5. In a holder for razor blades during honing and stropping, a strip of resilient metal doubled upon itself to form a pair of plates connected together at one end in a manner to prevent movement relative to one another in the plane of their adjacent surfaces, and between which a blade may be received, the free end of one plate normally tending to occupy a position spaced from the free end of the other plate in a direction normal to their surfaces; and a shank integral with the free end of each plate, one of said shanks being bent into channel shape in cross section to receive and frictionally grip the other shank, said other shank having a tongue stamped up therefrom to facilitate its disengagement from the first mentioned shank. 95

Signed at Niagara Falls, Ontario, this 5th day of March, 1925.

WALTER B. McFARLANE.
